TRIMMING MACHINE

Merrill N. Follansbee, Beverly, Mass., assignor to
United Shoe Machinery Corporation, Borough
of Flemington, N. J., a corporation of New Jersey

Application March 15, 1940, Serial No. 324,156

9 Claims. (Cl. 12—87)

This invention relates to trimming machines and is illustrated as embodied in a machine for trimming the edge of an insole attached to a last.

In the manufacture of some types of shoes, it is the usual practice to die out the insole so that its forepart will fit the last and so that the heel seat will be somewhat longer and wider than that of the last. After the insole has been attached to the last, the heel seat is trimmed so that it will conform to that of the last.

One object of the present invention is the provision, in a machine for performing this operation, of an improved last support which insures the proper presentation of a last and an attached insole to the trimming cutter regardless of the size of the last while requiring less skill on the part of the operator than must be exercised in present day machines.

In accordance with one feature of my invention, the last support is formed as a rigid U-shaped frame pivoted about an axis parallel to and below the axis of rotation of the cutter, with the arms of the frame extending upwardly toward the cutter. Rotatably carried at the upper end of one of the arms is a heel-seat-engaging member which is adjustably fixed against axial movement thereon, and rotatably carried at the upper end of the other arm of the U-shaped frame in axial alignment with the heel-seat-engaging member is a last-engaging member which is slidable toward and away from the heel-seat-engaging member for clamping a last and attached insole in the U-shaped frame. By so mounting the heel-seat-and last-engaging members, no portion of the supporting structure obstructs the operator's vision of the work as it is being trimmed, and, since the heel-seat-engaging member is fixed against axial movement, this member acts as a gage for insuring that the heel seat of the attached sole will always be in the proper predetermined plane regardless of different sizes of lasts.

In order to insure the proper predetermined location of this plane, provision is made for adjusting the U-shaped frame about a pivot which is at right angles to the axis of the cutter shaft and for adjusting the heel-seat-engaging member endwise.

These and other features of the invention, including certain details of construction and combinations of parts, will be described as embodied in an illustrated machine and pointed out in the appended claims.

In the drawings,
Fig. 1 is a front elevation of the upper portion

of a machine in which the invention is embodied;

Fig. 2 is a left side elevation of the upper portion of the machine showing in broken lines a sole in the process of being trimmed;

Fig. 3 is a view, partly in section, on a larger scale than Figs. 1 and 2 of the heel-seat-engaging member;

Fig. 4 is a section on the line IV—IV of Fig. 1 and the scale of Fig. 3; and

Fig. 5 is a view of the cutter acting upon a sole attached to a last, with the sole and a last to which it is attached held between the heel-seat and the last-engaging members.

The machine illustrated is provided with a cutter 10 and a shield 12 (Figs. 1 and 5) mounted at the outer end of a shaft 14 journaled in the upper end of a column 16. A guard 18 partially surrounds the cutter, this guard including a cylindrical portion 20 surrounding the shaft 14 on

which it is supported. A guide 22 is provided for engagement with the lateral surface of a last adjacent to the heel seat as indicated in Fig. 5, this guide including a lip 24 to hold the edge of the sole outwardly of the last during the trimming operation. The guide 22 is adjustably mounted in a frame 26 (Fig. 2) which is mounted on a pin 28 for swinging movement so that the guide may be swung outwardly away from the cutter to permit removal of the cutter. The pin 28 is mounted in a bracket 30 into which is also threaded a screw 38 passing through a hole in the frame 26. To lock the frame 26 with the guide 22 in operative position, a plate 40 passing through a slot in the side of the frame passes under the head of the screw 38.

For supporting a last and attached insole for presentation to the cutter 10, a supporting frame 40 is provided, this frame being U-shaped as indicated in Fig. 1 and including upwardly extending arms 41 and 42. The frame 40 is journaled on a pin 43 extending substantially parallel to the cutter shaft 14 to permit movement of the upper end of the frame toward and away from the cutter. The pin 43 is mounted in the upwardly extending parallel arms 44 and 46 of a support 48. Extending upwardly from the arm 44 of the support 48 is a pair of spaced arms 50 and 52 (Fig. 2), these arms being located at opposite sides of the frame 40. Screws 54 and 56 passing through the upper ends of the arms 50 and 52 form adjustable stops for limiting the swinging movement of the frame 40 about the pin 43. The frame 40 is normally held by gravity against the pin 56 in which position the last supported thereby is at a distance from the cut-

er.

Extending upwardly from the arm 44 of the support 48 is a pair of spaced arms 50 and 52 (Fig. 2), these arms being located at opposite sides of the frame 40. Screws 54 and 56 passing through the upper ends of the arms 50 and 52 form adjustable stops for limiting the swinging movement of the frame 40 about the pin 43. The frame 40 is normally held by gravity against the pin 56 in which position the last supported thereby is at a distance from the cut-

er.

ter 10. A handle 58 at the upper end of the arm 41 of the frame 40 enables the operator to swing the frame to move the last toward the cutter 10.

The support 48 is mounted on a pin 62 extending at right angles to the pin 43 and mounted in spaced upwardly extending arms 64 and 66 of a bracket 68 secured to a vertical plate 70 which is in turn secured by screws 72 to the side of the column 16. Screws 74 and 76 are threaded through the bracket 68 at opposite sides of the pin 62 and 10 are arranged to engage the under side of the support 48 to hold the support in adjusted position against movement about the pin 62. If desired, however, these screws may be backed off to permit limited swinging movement of the support 48 about the pin 62 so that the frame 40 may be swung in a plane parallel to the axis of the cutter shaft 14; but normally these screws will be so adjusted as to prevent swinging movement of the frame 40 in this manner.

A heel-seat-engaging member 80 (Figs. 1 and 3) is supported at the upper end of the arm 42 of the U-shaped frame 40. The heel-seat-engaging member includes a sleeve portion 82 terminating in a head 84 in which are mounted a plurality of pins 86 spaced around the longitudinal axis of the sleeve 82, these pins being arranged to penetrate the heel seat of the insole as shown in Fig. 5. The sleeve 82 is provided with a tapered bore 88 in which is received the correspondingly tapered end of a shaft 90 supported in a bracket 92 which is in turn slidably supported at the upper end of the arm 42. A screw 94 passes through a slot 96 in the bracket 92 and is threaded into the arm 42 to secure the bracket against movement with respect to the arm. The shaft 90 carries a ball bearing 98 which engages one end of the bracket 92 and a collar 100 secured to the outer end of the shaft 90 engages the other end of the bracket 92 and cooperates with the bearing 98 to prevent endwise movement of the shaft with respect to the bracket.

For holding a last and attached insole against the heel-seat-engaging member 80, a last-engaging member 102 is slidably mounted at the upper end of the arm 41 of the supporting frame 40 in axial alinement with the axis of rotation of the heel-seat-engaging member. The last-engaging member comprises a last pin 104 mounted in the end of a housing 106 (Fig. 4). A head 108 formed at the inner end of the last pin 104 engages a shoulder 110 in the housing 106 and a set screw 112 passing through the housing engages the last pin to secure the last pin in place. A collar 114 mounted on the last pin 104 engages the outer end of the housing 106 and is arranged to engage the cone of a last when the last pin is moved toward the heel-seat-engaging member 80 to clamp the last and attached insole thereagainst.

The housing 106 is rotatably supported at the outer end of a shaft 116 by means of ball bearings 118 and 120, these ball bearings being held at the end of the shaft 116 by a collar 122 and a screw 124 which forces the bearings against a shoulder 126 on the shaft 116. The ball bearings are maintained in spaced relation by a sleeve 128 surrounding the shaft 116. The housing 106 is maintained on the outer races of the ball bearings by a spring clamp 130 engaging the bearing 118. The housing has an internal shoulder which bears against the outer race of the bearing 120 and accordingly the housing is maintained against endwise movement with respect to the bearings.

A sleeve 132 is slidably mounted in the upper end of the arm 41 and at its outer end is provided

with an integral internally threaded collar 134. The shaft 116 has a reduced threaded portion at its outer end which engages the threads in the collar 134 so that lengthwise movement of the sleeve 132 will cause similar movement of the shaft 116 and the shaft and sleeve may therefore be moved together as a unit while the shaft 116 may be adjusted lengthwise with respect to the sleeve upon rotation of the shaft relative to the sleeve. In order to facilitate such rotation, a knob 136 is pinned to the outer end of the shaft 116. In order to move the sleeve 132 and the shaft 116 as a unit toward the heel-seat-engaging member 80, a handle 138 (Figs. 1 and 2) is provided. This handle is pivoted at 140 to the upper end of the arm 41 and is connected by links 142 and 144 to a plate 146 (Fig. 4), this plate being in turn secured by screws 148 to the collar 134 so that it is rigid with the sleeve 132. When the handle 138 is moved from the broken line position of Fig. 1 to the full line position, the sleeve 132 and shaft 116 are moved toward the right, thus causing movement of the last-engaging member 102 to clamp a last and attached insole against the heel-seat-engaging member 80.

The last-engaging member 102 is normally maintained in a retracted position in which the handle 138 assumes the broken line position of Fig. 1. For this purpose, the handle is provided with an extension 152 to which is connected a tension spring 154 the lower end of which is connected to a threaded pin 156 fixed to a bracket 158 extending laterally from the arm 41 of the supporting frame 40 by a nut 160. The spring 154 acts to urge the handle 138 in a counter-clockwise direction about the pivot 140 (Fig. 1) to the broken line position. In order to limit movement of the handle 138 by the spring 154, an adjustable stop screw 162 (Figs. 1 and 2) is threaded into a lug 163 connected to the extension 152 of the handle 138 and arranged to engage the surface 164 of the arm 41. Thus, when the handle 138 moves to the broken line position of Fig. 1 the inner end of the stop screw 162 engages the surface 164 of the arm 41 to prevent further movement of the handle 138 in this direction.

A hood 170 surrounds the rearward portion of the cutter 10 and a larger hood 172 is located below and rearwardly of the cutter. These hoods may be connected to a source of suction so as to collect and convey away the material removed from the insole by the cutter.

In using the machine, the support 44 will normally be held against movement about the pin 62 by the stop screws 74 and 76. By moving these screws in opposite directions, the support 48 may be tiltably adjusted about the pin 62 to obtain the proper angular relationship of the heel-seat-engaging member 80 and the rotary cutter 10. In order that the sole to be trimmed may be presented in the proper plane to the cutter, the heel-seat-engaging member may be adjusted lengthwise with respect to the cutter by loosening the screw 94 and adjusting the bracket 92 with respect to the arm 42 of the supporting frame 40. When the heel-seat-engaging member is properly located, each sole will be presented to the cutter in the same plane thus insuring uniformity in trimming.

In placing a last L with its attached insole I in the supporting frame 40, the frame will be in the position shown in Fig. 2, to which position it moves by gravity when permitted by the operator. The position assumed by the supporting frame at this time may be controlled by adjusting the

stop screw 56 against which the frame bears. The last is placed over the last pin 104 which at this time is held in its retracted position by the spring 154 with the handle 138 in the broken line position in Fig. 1. As the handle 138 is moved toward the handle 58 at the upper end of the arm 41, the last will be moved by the last-engaging member 102 toward the heel-seat-engaging member 80 to clamp the last and attached insole thereagainst. By pushing forwardly on the handles 138 and 58, the frame 40 is rotated about the pin 43 to move the work toward the cutter 10, as indicated by the broken lines of Fig. 2. By rotating the last about the axes of the heel-seat and last-engaging members, all portions of the heel seat of the insole may be presented to the cutter 10 to be trimmed thereby. Since the heel-seat-engaging member 80 is fixed against endwise movement relative to the cutter 10, the work will always be presented to the cutter in the same plane regardless of the height of the last to which it is attached. Since the support 44 is held against pivotal movement about the pin 62, the supporting frame 40 is movable only about the pin 43, thus obviating lateral guiding movement of the supporting frame by the operator. If it is desired to cause the last-engaging member 102 to be retracted further from the heel-seat-engaging member 80 to facilitate insertion of a higher last than that illustrated, the shaft 116 is adjusted axially relative to the sleeve 132 by rotating the knob 136 attached to the outer end of the shaft 116.

If it is desirable, as it may be when operating upon certain types of work, to permit tilting movement of the supporting frame 40 and the support 44 about the pin 62 during the trimming operation, the stop screws 74 and 76 may be backed away from the support 48. For most types of work, however, the support 48 may advantageously be fixed against tilting movement so as to render the trimming operation easier since the operator need guide the work in one direction only, thus insuring greater uniformity of trimming.

As is apparent in Fig. 1, by mounting the heel-seat and last-engaging members at the upper ends of the arms of the U-shaped frame 40, which frame is pivoted below the cutter 10, no portion of the supporting frame obstructs the operator's vision of the work during the trimming operation which permits the operator to ascertain immediately whether the trimming is being done properly.

Having described my invention, what I claim as new and desire to secure by Letters Patent of the United States is:

1. In a machine for trimming the edge of a sole attached to a last, a rotatable cutter, and means for presenting a sole attached to a last to said cutter to be trimmed thereby, said means comprising a rigid U-shaped supporting frame pivoted on an axis below and substantially parallel to the axis of rotation of said cutter, the arms of said frame extending upwardly from said axis, a sole-engaging member rotatably mounted at the upper end of one of said arms and held against endwise movement relative thereto, a last-engaging member rotatably and slidably supported in the upper end of the other arm of said supporting frame in axial alignment with said sole-engaging member, and means for moving said last-engaging member toward said sole-engaging member.

2. In a machine for trimming the edge of a sole

attached to a last, a rotatable cutter, and means for presenting a sole attached to a last to said cutter to be trimmed thereby, said means comprising a rigid U-shaped supporting frame pivoted on an axis below and substantially parallel to the axis of rotation of said cutter, the arms of said frame extending upwardly from said axis, a sole-engaging member rotatably mounted at the upper end of one of the arms of said supporting frame and held against endwise movement relative thereto, a last-engaging member rotatably and slidably supported in the upper end of the other arm of said supporting frame in axial alignment with said sole-engaging member, said last-engaging member comprising a pin arranged to enter the thimble in the heel end of the last and a collar on said pin for engagement with the cone of the last, and means for moving said last-engaging member toward said sole-engaging member.

3. In a machine for trimming the edge of a sole attached to a last, a rotatable cutter, and means for presenting a sole attached to a last to said cutter to be trimmed thereby, said means comprising a rigid U-shaped supporting frame pivoted on an axis below and substantially parallel to the axis of rotation of said cutter, the arms of said frame extending upwardly from said axis, a sole-engaging member rotatably mounted at the upper end of one of the arms of said supporting frame and held against endwise movement relative thereto, a last-engaging member rotatably and slidably supported in the upper end of the other arm of said supporting frame in axial alignment with said sole-engaging member, means for moving said last-engaging member toward said sole-engaging member, and means for enabling tilting adjustment of said supporting frame about an axis extending substantially at a right angle to the axis about which the supporting frame is pivoted.

4. In a machine for trimming the edge of a sole attached to the last, a cutter mounted for rotation about a substantially horizontal axis, a last-supporting frame, means supporting said frame for tilting movement about an axis substantially parallel to the axis of rotation of said cutter, said supporting means being mounted for tilting movement about a horizontal axis substantially perpendicular to the axis about which the supporting frame is tilted, means for adjustably locking said supporting means against tilting movement, and means carried by said supporting frame for supporting a last to which an insole has been attached for rotation about an axis substantially parallel to the axis of rotation of said cutter.

5. In a machine for trimming the edge of a sole attached to a last, a cutter rotatable about a horizontal axis, a last-supporting frame, means supporting said frame for tilting movement about an axis below and substantially parallel to the axis of said cutter, said supporting means being mounted for tilting movement about a horizontal axis substantially perpendicular to the axis about which the supporting frame is tilted, a pair of adjustable stops carried by said supporting means and arranged to engage the frame at opposite sides thereof to limit the tilting movement of said frame relative to said bracket, a second pair of adjustable stops arranged to engage said supporting means at opposite sides of the axis about which it is tiltably mounted to lock the supporting means against tilting movement, and means for supporting a last to which an insole

has been attached in the upper part of said supporting frame for rotation about an axis substantially parallel to the axis of said cutter with the sole in the plane of rotation of the cutter.

6. In a machine for trimming the edge of a sole attached to a last, a cutter rotatable about a horizontal axis, a U-shaped last-supporting frame, means pivotally supporting said frame about an axis below and substantially parallel to the axis of rotation of said cutter, said supporting means being mounted for tilting movement about a horizontal axis substantially perpendicular to the axis about which the frame is pivoted, means for locking said supporting means in a selected position against tilting movement, said locking means being adjustable to permit limited tilting movement of said supporting means within adjustable limits if desired, and means for supporting a last having a sole attached thereto in the upper part of said frame for rotation about an axis substantially parallel to the axis of rotation of said cutter with the sole attached thereto in the plane of rotation of the cutter.

7. In a machine for trimming the edge of a sole attached to a last, a cutter rotatable about a substantially horizontal axis, a U-shaped last-supporting frame, means pivotally supporting said frame for tilting movement about an axis substantially parallel to the axis of said cutter, said supporting means being mounted for tilting movement about a horizontal axis substantially perpendicular to the axis about which the frame is pivoted, means for locking said supporting means in a selected position against tilting movement, a sole-engaging means at the upper end of one of the arms of the frame rotatably mounted about an axis substantially parallel to the axis of rotation of said cutter, means adjustably securing said sole-engaging means against axial movement, a rotatable last-engaging member carried by the upper end of the other arm of said frame in axial alinement with said sole-engaging means, and means for moving said last-engaging member toward and away from said sole-engaging member.

8. In a machine for trimming the edge of a sole attached to a last, a cutter rotatable about a substantially horizontal axis, a guide adjacent to said cutter, said guide being constructed and arranged for engagement with the lateral surface

of the last adjacent to the heel seat, said guide including a lip arranged to hold the edge of the sole away from the last, a rigid U-shaped last-supporting frame pivoted for tilting movement about an axis below and substantially parallel to the axis of rotation of said cutter with the arms of the frame extending upwardly, a heel-seat-engaging member rotatably mounted in the upper end of one of the arms of said frame and fixed against axial movement relative to said arm, a last-engaging member rotatably carried by the upper end of the other arm of said frame in axial alinement with said heel-seat-engaging member and movable toward and away therefrom, and means enabling axial adjustment of the heel-seat-engaging member whereby a sole attached to a last and maintained in engagement with said heel-seat-engaging member will be properly presented to said cutter upon movement of said frame about its supporting pivot so that said guide will engage the edge of the last with the projection thereon between the last and the insole.

9. In a machine for trimming the edge of a sole attached to a last, a column, a drive shaft rotatably mounted at the upper end of said column about a substantially horizontal axis, a cutter mounted on said shaft adjacent to said column, a horizontally extending arm rigidly attached to said column below said cutter, a support pivoted on said arm about a horizontal axis substantially at a right angle to the axis of rotation of said cutter, a pair of adjustable stops between said arm and support for locking said support against movement relative to said arm, a last-supporting frame pivotally mounted in said support for tilting movement about an axis substantially parallel to the axis of said cutter, said supporting frame including a pair of spaced rigidly connected upwardly projecting arms, a sole-engaging member mounted at the upper end of one of said arms for rotation about an axis substantially parallel to the axis of rotation of said cutter and fixed against axial movement, a last-engaging member rotatably mounted at the upper end of the other of said arms and arranged for sliding movement coaxially of said sole-engaging member, and means for moving said last-engaging member toward and away from said sole-engaging member.

MERRILL N. FOLLANSBEE.
